DRIVING GEAR

Harry J. Criner and Harry E. Criner, Davenport,
Iowa, assignors of one-third to A. G. Bush,
Davenport, Iowa

Application September 3, 1936, Serial No. 99,189

12 Claims. (Cl. 74—78)

Our invention relates to improvements in driving gears.

The objects of our invention are:

To provide a driving gear which will revolve two shafts simultaneously, one of said shafts having a continuous uniform rotary movement and the other shaft having a rapid reciprocating rotary movement combined with a slow, substantially continuous progressive rotary movement in one direction of reciprocation; to provide simple means by which the rotating dolly of a reciprocating washing machine can be given a progressive forward movement simultaneously with its reciprocating movement; to provide means for rotating a shaft progressively forward and simultaneously reciprocating the shaft; to provide a combined worm and worm-gear operable simultaneously as a worm-gear and rack and pinion, with means for simultaneously rotating 20 and reciprocating the worm.

We accomplish these objects by the means illustrated in the accompanying drawing, in which,—

Figure 1 shows a longitudinal section of our gear on the line 1—1 of Figure 2;

Figure 2 shows a sectional elevation of our gear on the line 2—2 of Figure 1;

Figure 3 is a cross-sectional detail on the line 3—3 of Figure 2;

Figure 4 is a sectional detail of the brace, 21, on the line 4—4 of Figure 1.

Similar numerals refer to similar parts throughout the several views.

Our apparatus comprises a housing, 1, which may be of cast-iron or other suitable material and which may be united to a rigid base or cover plate, 2, in any desired manner.

Integral with the main housing, 1, we form a housing, 1a, for the drive-shaft, 3, and worm, 4, with suitable bearings, 3a, formed therein, for the motor-shaft, 3, on one end of which the worm, 4, is formed or splined or otherwise suitably secured.

The worm, 4, meshes with and drives the worm-gear-wheel, 5, which is secured upon the lower end of the shaft, 6. The shaft, 6, may be utilized to drive a wringer or other apparatus.

A hub, 2b, is formed integral with the cover plate, 2, which contains bearings, 7 and 8, in which the shaft, 6, revolves.

The wheel, 5, has suitably secured thereto or formed integral therewith, a bevel-gear-wheel, 9. A crank-pin, 13, is rigidly secured to the wheel, 5, 55 concentrically with the bevel-gear, 9, through

which it passes, and may be secured therein in any desired manner.

A rotatable shaft, 11, has one end revolvably mounted in one end of the bearing-block, 12, the other end of which forms a socket or bearing, 12a, which embraces the crank-pin, 13, while the intermediate portion, 12b, of the bearing-block, 12, forms a yoke, the two arms of which pass on opposite sides of the bevel-pinion, 10.

Upon the end of the shaft, 11, which acts as a connecting-rod, I mount a bevel-pinion, 10, which is rigidly secured to the shaft, 11, and meshes with the bevel-gear, 9.

The opposite end of the shaft, 11, has a worm, 17, formed thereon, which meshes with and actuates the worm-gear, 16, rigidly mounted upon the shaft, 14.

The shaft, 14, is splined or otherwise keyed to the wheel, 16, and the lower end of the shaft, 14, is mounted in a bearing, 15, preferably formed integral with the housing, 1. An additional bearing, 18, is formed integral with the base or cover plate, 2, and forms an upper bearing for the shaft, 14, above the base or cover plate.

The upper end of the shaft, 14, may be united in any desired manner to the lower end of any machine which it is desired to actuate thereby, such as the dolly of a washing machine.

The worm, 17, is held in mesh with the gear, 18, by a sleeve, 19, in which it is slidably and revolvably mounted. The sleeve, 19, has a lateral extension formed thereon, which is formed integral with a collar, 19a, which is pivotally mounted upon the shaft, 14, above the gear-wheel, 16. The sleeve, 19, is thus free to rock upon the shaft, 14, as a pivot.

Supports or braces, 20 and 21, may be formed integral with the base or cover plate, 2, by which the base plate, 2, can be rigidly secured to the body of any apparatus which it is desired to operate, such as a washing machine body.

The hub, 2a, may be threaded internally at its upper end to permit it to be rigidly secured to the bottom of a washing machine tub or to any other object to which it is desired to attach it by any suitable form of coupling.

In the operation of my machine, the motor or other prime-mover upon the shaft, 3, may be started, causing the shaft, 3, to revolve in either direction desired. As the shaft, 3, revolves, the worm, 4, will drive the worm-gear-wheel, 5. As the wheel, 5, revolves, it will carry the crank-pin, 13, and the fixed bevel-gear, 9, around in a circle.

As the gear, 5, revolves, the gear-wheel, 9,

will cause the gear, 10, to revolve and the gear, 10, will rotate the shaft, 11. As the shaft, 11, rotates, the worm, 17, will rotate, and as the worm, 17, rotates, it will cause the gear, 16, to 5 rotate with the shaft, 14.

With the arrangement shown, the shaft, 11, will rotate twice with each rotation of the gear, 5, but the relative rotation of the shaft, 11, and the gear, 5, may be varied by changing the relative 10 diameters of the bevel-gears, 9 and 10, and the length of travel of the gear, 9.

At the same time that the gear, 9, is rotating the gear, 10, the crank-pin, 13, will be carrying the head, 12a, of the block, 12, around in a circle, 15 which will cause the worm, 17, to slide backward and forward in the sleeve, 19, and the worm, 17, will act as a rack to reciprocate the worm-gear, 16, which will act as a pinion. In the meantime, the sleeve, 19, will rock upon its pivot, 14, so as 20 to accommodate the variation in angle caused by the different positions of the crank-pin, 13, and connecting-rod, 11.

When the ratio of the bevel-gear, 9, and bevel-gear, 10, is two to one, the shaft, 11, will be given 25 two complete rotations with each rotation of the shaft, 6, and the gear, 16, will accordingly travel a distance equal to two spaces upon the worm, 17, in addition to the forward and backward movement caused by the rack and pinion action 30 described.

It will thus be seen that with each reciprocation of the gear, 16, it will be advanced the distance occupied by two of its teeth and in case of a washing machine, a dolly attached to the 35 shaft, 14, will be proportionately advanced.

This action may be utilized and will be valuable in various types of machines, but has a particular value in the case of washing machines because of the tendency of the clothes to pack and tear 40 when the reciprocatory motion of the dolly is uniform. The effect of this progressive movement of the dolly which may be caused by our apparatus, will be to loosen up the clothes when bunched and to prevent the packing thereof in- 45 side of the washing machine.

Our apparatus will also tend to prevent rolling the clothes in a machine in a ball, and will aid in keeping them separated so as to improve the washing action thereof.

It should be noted that while we have shown the drive-wheel, 5, and the driven wheel, 16, as lying in the same plane, and the shafts, 6 and 14, as being parallel, this arrangement is not necessary, but our apparatus will permit a large variation 55 in relative angle of these wheels and shafts so long as the axes of the shafts are kept at right angles to the longitudinal axis of the connecting-rod, 11.

We do not limit our claims to the precise forms 60 shown in the drawing, as it is obvious that various modifications may be made without departing from the spirit of our invention, and our apparatus may be applied to various types of machines in cases where a progressive rotary action 65 is desired in connection with a reciprocatory action.

Our apparatus is designed to be operated preferably by a reversible electric motor, but the shaft, 3, may be driven by any desired form of 70 prime-mover and we do not limit our claims to an electrically driven machine.

We claim:

1. In a differential driving-gear, a supporting means, a pair of shafts rotatably mounted thereon, a drive-gear united to the lower end of the

first of said shafts, a planetary bevel-gear-wheel rigidly united to said drive-wheel and spaced eccentrically thereof, a crank-pin mounted in said drive-wheel concentric with the bevel-gear-wheel, a link member having one end pivoted upon the crank-pin and its opposite end forming a sleeve, a connecting-rod revolvably mounted in said sleeve and extending outwardly at both ends thereof and carrying a bevel-gear-pinion upon one end adapted to mesh with the bevel-gear-wheel and having its opposite end formed into a worm, a worm-gear-wheel mounted upon the corresponding end of the second shaft in mesh with the worm on the connecting-rod, a sleeve having a lateral extension pivoted upon the second shaft and adapted to guide and hold the worm in mesh with the worm-gear-wheel, and means for actuating the drive gear wheel. 5

2. In a differential driving-gear, a support, a shaft rotatably mounted thereon, a drive-gear wheel revolvably mounted in the support, a planetary bevel-gear-wheel rigidly united to one side of said drive-wheel and spaced eccentrically thereof, a crank-pin mounted in said drive-wheel concentric with the bevel-gear-wheel, a link member having one end pivoted upon the crank-pin and its opposite end forming a sleeve, a connecting-rod revolvably mounted in said sleeve and extending outwardly at both ends thereof and carrying a bevel-gear-pinion upon one end 20 adapted to mesh with the bevel-gear-wheel and having its opposite end formed into a worm, a worm-gear-wheel mounted upon the lower end of the shaft in mesh with the worm on the connecting-rod, a sleeve having a lateral extension pivoted upon the shaft and adapted to guide and hold the worm in mesh with the worm-gear-wheel, and means for actuating the drive-gear wheel. 25

3. In a differential driving-gear, supporting means, a pair of shafts rotatably mounted thereon, a drive-gear united to the first of said shafts, a planetary bevel-gear-wheel rigidly united to said drive-wheel and spaced eccentrically thereof, a crank-pin mounted in said drive-wheel concentric with the bevel-gear-wheel, a link member having one end pivoted upon the crank-pin and its opposite end forming a sleeve, a connecting-rod revolvably mounted in said sleeve and extending outwardly at both ends thereof and carrying a bevel-gear-pinion upon one end adapted to mesh with the bevel-gear-wheel and having its opposite end formed into a worm, a worm-gear-wheel mounted upon the corresponding part of the second shaft in mesh with the worm on the connecting-rod, a sleeve having a lateral extension pivoted upon the second shaft and adapted to guide and hold the worm in mesh with the worm-gear-wheel, and means for actuating the drive gear wheel. 40

4. In a differential driving-gear, supporting means, a vertical shaft rotatably mounted therein, a connecting-rod having one end formed into a worm, a worm-gear-wheel mounted upon the lower end of the shaft in mesh with the worm on the connecting-rod, a sleeve having a lateral extension pivoted upon the shaft and adapted to guide and hold the worm in mesh with the worm-gear-wheel, and means for continuously rotating the connecting-rod in one direction in a single horizontal plane and for driving it reciprocatingly longitudinally in the same plane. 45

5. In a differential driving-gear, supporting means, a shaft rotatably mounted therein, a connecting-rod having one end formed into a worm, 55

a worm-gear-wheel mounted upon the lower end of the shaft in mesh with the worm on the connecting-rod, a sleeve having a lateral extension pivoted upon the shaft and adapted to guide and hold the worm in mesh with the worm-gear-wheel, and unitary means for continuously rotating the connecting-rod in one direction in a single plane at a right angle to the shaft and for driving it reciprocatingly longitudinally in the same plane.

6. In a differential driving-gear, supporting means, a pair of shafts rotatably mounted thereon, a drive-gear united to one end of the first of said shafts, a planetary bevel-gear-wheel rigidly united to said drive-wheel and spaced eccentrically thereof, a crank-pin mounted in said drive-wheel concentric with the bevel-gear-wheel, a link member having one end pivoted upon the crank-pin and its opposite end forming a sleeve, a connecting-rod revolvably mounted in said sleeve and extending outwardly at both ends thereof and carrying a bevel-gear-pinion upon one end adapted to mesh with the bevel-gear-wheel and having its opposite end formed into a worm, and means united to the second shaft whereby the rotary and reciprocating motion of the connecting-rod when driven by the bevel-gears and crank-pin, may be transmitted to the second shaft and cause a reciprocating rotary movement thereof and also a progressive rotational movement with each reciprocation thereof.

7. In a differential driving-gear for a shaft, the combination with a housing, of a shaft carrying a worm-gear-wheel mounted in said housing, a sleeve having an extension formed thereon pivotally mounted upon said shaft, a connecting-rod having a worm formed upon one end thereof and slidably and rotatably mounted in 40 said sleeve, in mesh with the gear-wheel, and means for simultaneously reciprocating and rotating said connecting-rod in a single plane at a right angle to the shaft.

8. Means for securing a differential reciprocating rotary action of a shaft which consists in securing a worm-gear to such shaft and securing a worm in mesh with such worm-gear, in combination with means for simultaneously recipro-

cating longitudinally and rotating the worm in a single plane at a right angle to the shaft.

9. Means for simultaneously reciprocating and rotating a worm which consists in forming said worm upon a connecting-rod and subjecting it to reciprocating action by a crank and crank-pin suitably coupled to the connecting-rod, and rotating the connecting-rod by the rotation of a bevel-pinion secured upon such rod in mesh with a planetary bevel-gear mounted adjacent to and concentric with the crank-pin.

10. In a mechanical movement, horizontal drive and driven gear-wheels, means by which the drive wheel may cause a simultaneous reciprocatory rotary and a progressive rotary movement of the driven wheel comprising a rotatable connecting-rod having one end pivotally linked to a crank-pin carried by the drive wheel and carrying a bevel-pinion meshed with a bevel-gear-wheel rigidly united to the drive wheel concentric with crank-pin, and carrying on its other end a worm meshing with the driven wheel.

11. In a mechanical movement, drive and driven gear-wheels mounted in the same plane, means by which the drive wheel may cause a simultaneous reciprocatory rotary and a progressive rotary movement of the driven wheel comprising a rotatable connecting-rod having one end pivotally linked to a crank-pin carried by the drive wheel and carrying a bevel-pinion meshed with a bevel-gear-wheel rigidly united to the drive wheel concentric with crank-pin, and carrying on its other end a worm meshing with the driven wheel.

12. In a mechanical movement, a support, a drive and driven gear-wheels mounted thereon and spaced apart, and means by which the drive wheel may cause a simultaneous reciprocatory rotary and a progressive rotary movement of the driven wheel comprising a rotatable connecting-rod having one end pivotally linked to a crank-pin carried by the drive wheel and carrying a bevel-pinion meshed with a bevel-gear-wheel rigidly united to the drive wheel concentric with crank-pin, and carrying on its other end a worm meshing with the driven wheel.

[Official Gazette March 7, 1939.]

a worm-gear-wheel mounted upon the lower end of the shaft in mesh with the worm on the connecting-rod, a sleeve having a lateral extension pivoted upon the shaft and adapted to guide and hold the worm in mesh with the worm-gear-wheel, and unitary means for continuously rotating the connecting-rod in one direction in a single plane at a right angle to the shaft and for driving it reciprocatingly longitudinally in the same plane.

6. In a differential driving-gear, supporting means, a pair of shafts rotatably mounted thereon, a drive-gear united to one end of the first of said shafts, a planetary bevel-gear-wheel rigidly united to said drive-wheel and spaced eccentrically thereof, a crank-pin mounted in said drive-wheel concentric with the bevel-gear-wheel, a link member having one end pivoted upon the crank-pin and its opposite end forming a sleeve, a connecting-rod revolvably mounted in said sleeve and extending outwardly at both ends thereof and carrying a bevel-gear-pinion upon one end adapted to mesh with the bevel-gear-wheel and having its opposite end formed into a worm, and means united to the second shaft whereby the rotary and reciprocating motion of the connecting-rod when driven by the bevel-gears and crank-pin, may be transmitted to the second shaft and cause a reciprocating rotary movement thereof and also a progressive rotational movement with each reciprocation thereof.

7. In a differential driving-gear for a shaft, the combination with a housing, of a shaft carrying a worm-gear-wheel mounted in said housing, a sleeve having an extension formed thereon pivotally mounted upon said shaft, a connecting-rod having a worm formed upon one end thereof and slidably and rotatably mounted in 40 said sleeve, in mesh with the gear-wheel, and means for simultaneously reciprocating and rotating said connecting-rod in a single plane at a right angle to the shaft.

8. Means for securing a differential reciprocating rotary action of a shaft which consists in securing a worm-gear to such shaft and securing a worm in mesh with such worm-gear, in combination with means for simultaneously recipro-

cating longitudinally and rotating the worm in a single plane at a right angle to the shaft.

9. Means for simultaneously reciprocating and rotating a worm which consists in forming said worm upon a connecting-rod and subjecting it to reciprocating action by a crank and crank-pin suitably coupled to the connecting-rod, and rotating the connecting-rod by the rotation of a bevel-pinion secured upon such rod in mesh with a planetary bevel-gear mounted adjacent to and concentric with the crank-pin.

10. In a mechanical movement, horizontal drive and driven gear-wheels, means by which the drive wheel may cause a simultaneous reciprocatory rotary and a progressive rotary movement of the driven wheel comprising a rotatable connecting-rod having one end pivotally linked to a crank-pin carried by the drive wheel and carrying a bevel-pinion meshed with a bevel-gear-wheel rigidly united to the drive wheel concentric with crank-pin, and carrying on its other end a worm meshing with the driven wheel.

11. In a mechanical movement, drive and driven gear-wheels mounted in the same plane, means by which the drive wheel may cause a simultaneous reciprocatory rotary and a progressive rotary movement of the driven wheel comprising a rotatable connecting-rod having one end pivotally linked to a crank-pin carried by the drive wheel and carrying a bevel-pinion meshed with a bevel-gear-wheel rigidly united to the drive wheel concentric with crank-pin, and carrying on its other end a worm meshing with the driven wheel.

12. In a mechanical movement, a support, a drive and driven gear-wheels mounted thereon and spaced apart, and means by which the drive wheel may cause a simultaneous reciprocatory rotary and a progressive rotary movement of the driven wheel comprising a rotatable connecting-rod having one end pivotally linked to a crank-pin carried by the drive wheel and carrying a bevel-pinion meshed with a bevel-gear-wheel rigidly united to the drive wheel concentric with crank-pin, and carrying on its other end a worm meshing with the driven wheel.
